UNITED STATES PATENT OFFICE.

WALTER K. FREEMAN, OF BROOKLYN, NEW YORK, ASSIGNOR TO WILLIAM S. HADAWAY, JR., TRUSTEE, OF BOSTON, MASSACHUSETTS.

DYNAMO-ELECTRIC MACHINE.

SPECIFICATION forming part of Letters Patent No. 440,424, dated November 11, 1890.

Application filed September 20, 1890. Serial No. 365,672. (No model.)

To all whom it may concern:

Be it known that I, WALTER K. FREEMAN, a citizen of the United States, and a resident of Brooklyn, in the county of Kings and State 5 of New York, have invented certain useful Improvements in Dynamo-Electric Machines; and I do hereby declare the following to be a full and exact description of the same, which will enable others skilled in the art to which 10 the invention appertains to make and use the same.

My invention relates particularly to improved means for securing the coils upon the cores of the field-magnets of a dynamo-electric machine.

In dynamo-machines as usually constructed the cores of the field-magnets are rigidly secured to or formed integral with the keeper, and the coils are slipped upon the cores and 20 are held in place by a head, which is usually either secured to the core by screws or pins or by means of bolts passed through the head on the outside of the cores and through the keeper. Where screws or pins are employed, 25 the vibrations and strains to which they are subjected during the running of the machine frequently cause them to become broken or loosened and permit the heads and the coils to drop down upon the armature. On the 30 other hand, where the outside bolts are used they are unsightly and, being exposed, afford surfaces for the accumulation of dust from the machine, and on these accounts are objectionable.

The object of my invention is to so construct and dispose the means by which the coils are held in place upon their cores as that they will be stronger and more secure than heretofore, and at the same time be entirely 35 concealed from view and from the access of dust from the machine.

To this end my invention consists in the novel construction and combinations of parts hereinafter described, and pointed out specifically in the clauses of the claim at the close 45 of this specification.

Referring to the accompanying drawings, Figure 1 represents a segment of the keeper of the field-magnets of an alternating-current 50 dynamo, showing three cores, one of which—the right-hand one—is covered by a coil se-

cured in accordance with my invention; another—the middle one—showing the coil-securing appliances with the coil removed, and the third or remaining one appearing without 55 either coil or securing appliances. Fig. 2 is a plan view of the removable head of one of the coils. Fig. 3 is a view of one of the securing-bolts and its nut. Fig. 4 is a cross-sectional view taken on the line *xx*, Fig. 1. 60

Similar letters of reference in the several figures indicate the same parts.

The letter A indicates the keeper of the field-magnets; B, the cores, formed integral therewith and constructed, preferably, of tapering form, as shown.

C are the coils of wire adapted to be slipped upon the cores, and D are the heads which, in connection with the bolts E and nuts F, hold the coils in place upon their respective 70 cores.

The bolts E, instead of passing through the heads D on the outside of the coils as formerly, in my present invention pass through inwardly-projecting lugs G on said heads, as 75 shown in Fig. 2, and thence through grooves or channels H, formed in the sides of the cores B, as shown in Fig. 1, and thence through the keeper A, where they receive the nuts F, as shown in Figs. 1 and 4. The heads e of 80 the bolts E are countersunk flush with the surface of the lugs G, and for the purpose of securing a firmer connection between the parts the said lugs G are extended beyond the surface of the heads D and caused to enter 85 sockets h in the cores B, as represented in Figs. 1 and 4. In assembling the parts the coils are first slipped upon the cores, then the heads are put in position, and, finally, the bolts E are inserted through the lugs of the 90 heads and secured by the application of the nuts to their outer ends, as shown in Fig. 1. It will be observed that in this construction the bolts are entirely hid from view, and that the lateral support afforded by the grooves 95 H, as well as the further lateral support afforded by the co-operation of the lugs G with the sockets h, prevents the displacement of the heads and renders the whole connection very strong and secure.

While my invention is herein shown as applied to the field-magnets of a dynamo-elec-

tric machine, it is evident that the principle of securing the coil upon its core is of wider and more general application.

Having thus described my invention, what I claim as new is—

- 5 1. The combination, substantially as described, of a core, a coil, a removable head surrounding the pole of the core for holding the coil upon the core, and bolts by which the head is held in place passed through the head on the inside of the coil, as set forth.
- 10 2. The combination, substantially as described, of a grooved core, a coil, a removable head for holding the coil upon the core, and bolts passed through the head and through the grooves in the core, as set forth.
- 15 3. The combination, substantially as described, of a grooved core, a coil, a removable head for holding the coil upon the core pro-

vided with the perforated lugs, and the bolts 20 passing through the lugs of the head and the grooves of the core, as set forth.

4. The combination, substantially as described, of the core having the grooved sides and the sockets for the lugs of the head, the 25 coils, the head having the perforated lugs, and the screw-bolts, as set forth.

5. In a dynamo-machine, the combination, with the keeper provided with the cores, of the coils surrounding the core, the removable 30 heads overlying the coils to retain them on the cores and provided with the perforated lugs, and the screw-bolts passing through said lugs and engaging the keeper, as set forth.

WALTER K. FREEMAN.
